MULTIPLE RECORD PHONOGRAPH

Arthur C. Ansley, New York, N. Y.

Application May 20, 1935, Serial No. 22,349

7 Claims. (Cl. 274—10)

This invention relates to phonographs adapted to play automatically both sides of a plurality of records successively.

One of the objects of the invention is to provide a device of this sort in which records of different diameters such as a standard ten or twelve inch record may be successively played on both sides without turning the record over.

A feature of the invention resides in the provision of means for supporting a record in two playing positions and providing one stylus for operating on the under side of one record while supported in one position and another stylus for playing the other side of the same record when supported in a second position.

Further features of the invention relate to the means for determining the position of the active stylus for playing either a ten inch record or a twelve inch record together with means for withdrawing the active stylus to permit the record which has been played on one side to be positioned to be played on the other side without turning the record over.

The invention may be embodied in various forms and the accompanying drawings are illustrative of one form by which the objects may be attained but the particular mechanism shown and hereinafter described may be varied without departing from the principle of the invention.

30 In the drawings, Figure 1 is an elevation showing the enclosing casing in section.

Figure 2 is a view partly in elevation and partly in section as viewed along the line 2—2 of Figure 1.

35 Figure 3 is a section on the line 3—3 of Figure 2.

Figure 4 is a section on the line 4—4 of Figure 1.

Figure 5 is a section on the line 5—5 of Figures 1 and 7.

Figure 6 is a section on the line 6—6 of Figure 5.

Figure 7 is a section on the line 7—7 of Figure 2.

40 Figure 8 is a section on the line 8—8 of Figure 7.

Figure 9 is a section on the line 9—9 of Figures 1 and 7.

Figure 10 is a section on the line 10—10 of Figure 2.

Figure 11 is a section on the line 11—11 of Figure 10.

Figure 12 is a section on the line 12—12 of Figure 1.

55 Figure 13 is an enlarged detailed elevation of

the manually settable knobs for controlling the proper playing of the records and the automatic throwing out of the record changing mechanism when the last record has been played.

Figure 14 is a section on the line 14—14 of 5 Figures 4 and 13.

Figure 15 is a detail view of the escapement mechanism for lowering a lower record supporting turn table and is taken on the line 15—15 of Figure 1.

Figure 16 is a section on the line 16—16 of 10 Figure 15.

Figure 17 is a detail showing the escapement dogs of Figure 15 in a different operative position.

15 Figures 18 and 19 are enlarged detailed views showing the means for permitting one record at a time to drop from the upper position to the lower position, these views being taken on the line 18—18 of Figure 1 and showing the parts 20 in different operative positions.

Figure 20 is a similar view showing the position of the parts when ready for reloading.

Figure 21 is a detailed section on the line 21—21 of Figure 18.

25 Figure 22 is a section on the line 22—22 of Figure 18.

Figure 23 is a more or less diagrammatic representation of the mechanism particularly in reference to the electrical circuits and their means 30 of control; and

Figure 24 is a diagrammatic view illustrating the action of the various cams.

For the purpose of giving a general idea of the functions performed in the automatic playing of 35 a plurality of records and before describing the various mechanisms in detail, it may be stated that the records to be played are manually assembled and are held in the position shown in Figure 1, it being understood, of course, that the 40 assembly is to be made in the order in which the records are desired to be played. A switch is then manually closed which starts a motor, the latter controlling all of the automatic parts of the device. The motor turns the record supporting 45 means and a shaft to be designated the cam shaft. The cam shaft during 180° of its movement, operates to determine first the position of the tone arm for a record of larger or smaller diameter. This is done by means of a feeler and the position which the feeler takes determines the amount 50 of movement given to the tone arm. The stylus and tone arm are then moved into playing position and after playing a record, means are brought into operation under control of the same 55

cam shaft for withdrawing the stylus from contact with the record, moving the tone arm out of playing position and causing the record which has just been played to be dropped to a lower supporting means.

6 A lower tone arm is then brought into operation and the same movements are repeated. In addition to the record supporting means, the tone arm supporting shaft and the cam shaft, a fourth 10 shaft which will be designated as a control shaft, is provided. This shaft is operated intermittently to control the proper change in the electric circuits.

15 As each record is played in its lower position, the turn table supporting the record is moved down the thickness of one record so that the tone arm always moves in and out of playing position in the same plane. When the last record has been played or when the turn table reaches a position determined by the setting of the left-hand knob shown in Figure 13, the circuit operating the cam shaft and the control shaft is broken. The circuit through the motor, however, is not interrupted automatically, the motor being 25 stopped by manipulation of a switch.

20 Referring to Figures 1 and 7, the casing represented generally by the numeral 2 is provided with a hinged portion 3, (Figure 1) permitting the upper part of the casing to be turned back in order 30 to enable the records to be loaded on to the record shaft 4. This shaft, as shown in Figure 7, is divided at the point where the casing is designed to be separated. The lower portion of the shaft is provided with a depression into which fits a centering pin 5 carried by the upper portion of the shaft. The upper and lower portions of the shaft 4 are driven in opposite directions by the motor 6.

Drive for the record rotating means

40 Referring to Figure 1 the shaft 4 carries a bevelled gear 7 engaging a similar bevelled gear 8 on a shaft 9, the left hand end of which carries a bevelled gear 10 meshing with a similar gear 11 on a vertical shaft 12. This shaft 12 passes through a bracket 13 projecting from the side frame, the bracket being provided with an aperture through which the shaft 12 passes with ample clearance. Supported by the bracket 13 is a guiding sleeve 14 which acts as a bearing for the upper portion of the shaft 12, the end of the shaft being provided with a collar 15 carrying a pin 16 projecting from its upper surface. The hinged portion of the casing carries a shaft 17 supported by an upper bracket 18 and a lower bracket 19. 50 The lower end of the shaft 17 is provided with a collar 20 similar to the collar 15 and a pin 21 projects from the underside of this collar and is adapted to be engaged by the pin 16 so that the shaft 12 and shaft 17 are driven as one shaft when the casing is closed. The upper portion of the shaft 17 is provided with a bevelled gear 22 engaging with a slightly larger bevelled gear 23 on the shaft 24. The shaft 24 is supported by the bracket 18 and by a similar bracket 25 connected to the casing. The upper portion of the shaft 4 is also supported in the bracket 25 which carries a bevelled gear 26 meshing with a similar gear 27 on the shaft 24. By this train of gearing the lower and upper portions of the shaft 4 are driven 60 in opposite directions as is necessary in order to play standard records.

Record feeding

As shown in Figure 7 the upper portion of the 75 shaft 4 is centrally bored and mounted within this

bore is a plunger 28 having a knob 29 at its upper end whereby the plunger may be operated manually. The lower end of the plunger, as better shown in Figures 18, 19, and 20, is provided with a head 30 cooperating with a series of members 31 and a series of balls 32. (See also Figures 21 and 22.)

When the plunger is in the position shown in Figures 7 and 17, a cylindrical enlargement 41 thereof acts against the balls 32 and forces them to the position shown in these figures and also in Figure 22. In this position the balls 32 engage the under surface of the lowermost record and support all of the records above it. A presser plate 34 having a hub 35 loosely engaging the upper portion of the shaft 4, holds the records in place.

In the present embodiment of the invention ten records may be placed at one time under the presser plate 34 and these records may be ten 20 inch records or twelve inch records and may be loaded on the shaft 4 in any desired order. The twelve inch records are indicated by the reference character 36 and the ten inch records by the character 38. In the position of the parts 25 shown in Figure 17, the under side of the lowermost record is in playing position and after it has been played, mechanism is brought into operation automatically to move the plunger 28 from the position shown in Figure 18 to the position 30 shown in Figure 19. When so moved its upper conical portion 39 acts on the members 31 which are at this time within the central opening of the record next above the lowermost record. When the plunger has reached the position 35 shown in Figure 19, the central cylindrical portion of the head thereof is in engagement with the members 31 and wedges them against the edge of the aperture in the record second from the bottom and at the same time the wider cylindrical portion 41 of the head releases the balls 32 and permits the lowermost record to drop by gravity onto the turn table 42, splined at 43 to the lower portion of the shaft 4.

The members 31 have cylindrical portions 33 45 to maintain them in proper position within the central recess in a record.

The mechanism for moving the plunger from the position shown in Figure 18 to the position shown in Figure 19 consists of a lever pivoted at 50 44 in a bracket 45 (Figure 7) said lever having a horizontally extending arm 46, the left end of which engages a notch in a grooved collar 47 attached to the plunger 28. A vertical arm 48 of the lever 46 is engaged by a compression spring 49 and holds the arm 46 against a stop 50 having a handle 51 by which it may be moved manually to inoperative position when it is desired to reload the records.

55 The movement of the plunger is brought about by a solenoid 52 whose armature 53 is connected to the arm 46 as shown in Figures 1 to 7. The solenoid 52 is energized at the proper time by means to be hereinafter described and the arm 46 is pulled down until its movement is limited 65 by a stop 54 connected to some stationary part of the cabinet. When the arm is thus positioned against the stop, the plunger is in the position shown in Figure 19.

During this movement of the plunger the lowermost record shown in Figure 18 drops by gravity onto the turn table 42. The balls 32, at this time are free to take the position shown in Figure 19. When the solenoid is deenergized, the spring 49 moves the parts controlled thereby back 75

to the position shown in Figures 1 and 7, the balls 32 being again moved to the position shown in Figure 18, by the enlargement 41 on the plunger head.

5 *Reloading the records*

When it is desired to reload the machine, the knob 51 is moved to the right from the position shown in Figures 1 and 7, the casing being slotted to permit this movement and the hinged portion of the casing is then swung back about 180°. The knob 29 is then pressed up (the position of the parts shown in Figure 1 being at this time reversed) and this movement of the knob causes the plunger head 30 to take the position shown in Figure 20 releasing the members 31 and the balls 32. The records are then loaded on to the shaft 4 in the reverse order in which they are desired to be played. The casing is then closed and the machine is ready to begin its automatic action of the successive playing of the records. It may be mentioned that the collars 15 and 20 (Figure 1) are for the purpose of permitting the connection between the shafts 12 and 17 to be broken during the loading operation and restored when the casing is again closed.

10 *Circuits and control cams*

The automatic operation is started by moving a switch 56 from the position shown in Figure 1 to the position shown in Figure 23. This closes circuits which start the motor 6 and cause the cam shaft 57 to be rotated. The closing of the switch 56 establishes a circuit for starting the rotation of the cam shaft which circuit may be traced as follows: from the positive source of supply shown in Figure 23 along the wire 59 and through the closed contact at 60, to a bus bar 61, thence along wire 62 to conducting segment forming part of a disc 64 carried by control shaft 65 (Figures 1, 7, and 23). By means of the electrically conducting segment, the current passes to wire 66, through the closed switch 67, to the wire 68 and thence to the solenoid 70. The return circuit from the solenoid 70 includes the wire 71 connected to a bus bar 72 to which is connected the wire 73 which leads directly to the negative side of the circuit.

The contact at 60 is closed as long as the hinged portion of the casing is in normal position shown in Figures 1 and 7. When this portion of the casing, however, is swung back during the period of reloading, the contact at 60 is broken thereby breaking the motor circuit and at the same time breaking all other circuits which pass through the bus bar 61.

A circuit to the motor is established by means of wire 59, contact 60, bus bar 61, wire 75 to the motor in-lead 76, through the motor to the out-lead 78, then along wire 80 to the bus bar 72 and wire 73 to the negative side of the circuit.

The cam shaft designated by the reference character 57 is supported in an upper bearing 81 (Figures 1 and 7) and a lower bearing 82 (Figure 1). Immediately above the bearing 82 the shaft is provided with a collar 84 pinned thereto and provided with clutch teeth (see Figures 1 and 23). Surrounding the lower portion of the shaft 57 is a sleeve 85 (Figure 7) having fixed thereto a flanged collar 86. A bracket 87 forming part of the casing supports the sleeve, an anti-friction washer 88 being placed between the flange of the collar 86 and the bracket. The bracket is apertured to permit the sleeve to revolve freely therein. At its lower end, as shown

in Figure 1, the sleeve 85 carries a collar 89 having a clutch face similar to the clutch face on the collar 84 (Figures 1 and 12). Between collars 84 and 89 there is provided a gear 92 having an elongated hub 93 carrying clutch faces adapted respectively to engage with the clutch face on the collar 89 or on the collar 84. The hub 93 and gear 92 are loosely mounted on the shaft 57 and normally neither of the clutches are engaged, the parts being in neutral position as shown in Figure 1. To maintain them in this position or to return them to this position when actuated, the hub 93 is provided with a groove adapted to be engaged by the forked end of a lever 94 pivoted at 95 and urged to neutral position by two arms 96 pivoted at 97. A spring 98 tends to move these arms towards each other until limited by a stop 99. When both arms 96 make contact with the stop 99, the hub 93 is in its central or neutral position shown in Figure 1. When the circuit is established as above outlined through the solenoid 70, the hub 93 is moved to the position shown in Figures 13 and 23 with the clutch face on collar 84 active. This causes the cam shaft 57 to be rotated, the drive being effected from the motor 6 through the medium of a pinion 100 meshing with the gear 92. The pinion 100 is driven through bevelled gearing 101 which is connected through a reducing gear box 102 through the bevelled gear 103 in mesh with the bevelled gear 1 on the shaft 4.

Since the collar 84 is pinned to the shaft 57, it follows that the energization of the solenoid 70 with consequent movement of the parts to the position shown in Figures 12 and 23, results in the rotation of the shaft 57. This shaft carries a sleeve 106 pinned thereto at 107 (Figure 7) so that the sleeve 106 rotates whenever the shaft 57 rotates.

Since the present invention contemplates playing both sides of a record by different tone arms, means must be provided for bringing the tone arms into operation at the proper time and retracting them to normal position after they have performed their function. In the present embodiment the sleeves 85 and 106 carry a series of identical cams which operate during 180° rotation of either sleeve, to move the proper tone arm to playing position after which the operative sleeve is temporarily stopped.

In the present embodiment also the several cams are arranged on their respective sleeves in the order best adapting them to perform their function and not necessarily in the order in which the various functions performed by the respective cams take place. In the following description, therefore, the cams will be described in the order in which they function without regard to their position on the sleeves 85 and 106.

65 *Positioning a tone arm for playing different sized records*

Since a record to be played may be for instance, either a ten inch record or a twelve inch record and since the tone arm must be differently positioned according to the size of the record to be played, the first operation after the solenoid 70 is actuated and the sleeve 106 starts rotating, is to select that tone arm cam for operation which will move its tone arm to the proper initial position.

70 This selection is brought about by a feeler mechanism which determines whether the tone arm is to be initially positioned for playing one

size record or another size record. For this purpose the sleeves 85 and 108 carry each a feeler cam 108 (Figures 5 and 7) which is circular through the greater portion of its periphery but is provided with a depressed portion 109 extending about 90° of its circumference.

The various cams for controlling both the upper and lower tone arms are designated by the same reference character since they are alike in construction and function. The upper set of cams will be first described since in the normal operation of the device, it is the under side of the upper record that is first played.

The upper and lower tone arm shafts 110 are supported by brackets 111 and 112 (Figure 7). Loosely mounted on each shaft 110 is a feeler 113 (Figures 5 and 23). A spring 114 secured to a pin on the lower end of the feeler and anchored to the bracket 111 tends to rotate the feeler 20 about the shaft 110 in an anti-clockwise direction as viewed in Figure 5. A forked link 116 carrying a stud 118 is connected to each feeler at 115, the forks 117 of which link embrace the sleeves 85 and 108 thereby to guide each link 25 in its movement as controlled by its cam 108 and spring 114. When the cam 108 has made about a 45° rotation, (see Figure 24) the depression 109 permits the spring 114 to act but if the record which is in the same plane as 30 the feeler, happens to be of a larger size, the feeler will merely contact with the periphery of the record and will be moved but a very slight amount, being held from movement by the record. If, however, a record of smaller size is in 35 the plane of the feeler 113, the cam depression 109 will permit the feeler to move a greater distance under stress of its spring 114 and cause a circuit to be closed through the contacts 118 (Figures 5 and 23). When a feeler 113 is in 40 normal position, a non-conducting portion 120 is in engagement with the contacts as shown in Figure 5.

Before describing the action of the cams which move the tone arm to different positions, it will 45 be desirable in the interest of clearness to refer to the construction of the tone arm.

The lower end of the upper shaft 110 is forked at 121 (Figure 7) and the upper tone arm 122 is supported by gimbals 123 within these forks. 50 Near the center of the upper shaft 110 is a collar 124 secured to the shaft (shown also in Figure 10). The cams for controlling the movement of the shaft 110 and hence the tone arm connected thereto are indicated at 125 and 126 (Figure 7). These cams are box cams and are alike except that the cam 126 has a greater throw than the cam 125. Each cam is engaged by a roller 128 (Figure 8) carried by forked links 129 which are connected to arms 130 and 131 having hubs 132 and 133 which loosely engage the shaft 110. The hub 132 of the arm 130 is mounted below the fixed collar 124 and the arm 131 and hub 133 are mounted above said fixed collar as shown in Figures 7 and 10.

65 The position of the feeler 113 determines whether the fixed arm 124 is to be connected with the arm 130 or the arm 131. Normally the fixed arm is connected to the arm 130 as shown in Figure 10, such connection being effected by a latch 70 135 pivoted to the fixed arm at 136 and urged by a spring 137 to the position shown in Figure 10, where it is engaged within a notch in the arm 130. Both arms 130 and 131 are moved when the cams 125 and 126 rotate but the movement of the arm 131 is an idle movement. The movement 75

of the arm 130 on the other hand causes the fixed arm 124 to be moved with it and hence the shaft 110 and the tone arm 122. While the above description refers more particularly to the upper tone arm shaft, it is equally applicable to the lower tone arm shaft, the parts being duplicates of each other.

The contour of the cam 125 is such that the tone arm is moved from the inoperative dotted line position indicated at (a) Figure 8 to the dotted line position indicated at (b).

If on the other hand a ten inch record is in a position to be contacted by the feeler 113, the depression 109 in the cam 108 permits the feeler to be moved by its spring 114 to the position shown in Figure 23. This causes the contacts 118 to be bridged by the conducting portion of the feeler and a circuit is closed through a solenoid 138 (Figures 10, 11, and 23). This circuit may be traced as follows: from the positive side of the 20 line through wire 59, contact 60, and bus bar 61 to wire 140, contacts 118 to upper solenoid 138, wire 141 to bus bar 72 and the wire 73 to the negative side of the circuit.

The action of the cams 125 and 126 is diagrammatically shown in Figure 24 and the relative time when these cams begin to operate and when such movement ceases. It will be noted that after the selection of the proper record has been brought about by the feeler 113, the cams 125 or 126, according to which one is selected by the feeler, will begin to operate to position the tone arm in playing position. It will also be noted that the cams have a relatively steep drop to about the position indicated at 135° (Figure 35 24) and from that position to the 180° position they are circular. At the 180° position, however, there is a drop indicated at 142 which is provided for the purpose of permitting the tone arm to be 40 further moved in the same direction as previously moved by this cam, such further movement being under control of the sound groove in the record.

During the time that the cam 125 or 126 as the case may be, is moved along its circular portion and for that reason having no effect on the position of the tone arm, the latter is rocked on its gimballed supports 123 to permit the upper stylus 144 to move into contact with the record groove. A spring 145 (Figure 1) normally tends to move 50 this stylus into contact with the record groove but the action of this spring is resisted by a cam 146 (Figures 1, 5, and 7). This cam acts on a roller 147 carried by a bell crank lever pivoted at 148 to an extended portion 149 of the bracket 55 111. The bell crank has an arm 150 which bears against a roller 151 on the tone arm and normally holds the stylus away from the record against the tendency of the spring 145 to move it into contact therewith. This applies only to 60 the upper tone arm. The arm 150 of the bell crank controlling the lower tone arm operates to hold the tone arm away from the record against the force of gravity and no spring is needed. Otherwise the upper tone arm and the lower tone 65 arm are controlled in the same way.

The cam 146 releases the tone arm to permit it to engage the record when the cam has moved through 180° and at this point the cam has a depression 152 (Figures 5 and 24) which permits the bell crank to move away from the roller 151.

70 Since any further movement of the cam 146 would act to withdraw the stylus from the record, provision must be made for stopping the ro- 75

tation of the sleeve 106 and its various cams while an upper record is being played.

For this purpose a disc 154 (Figures 1, 7, and 9) is secured to the sleeve 106, said disc being provided with two oppositely positioned notches shown in full in dotted lines in Figure 9. This disc 154 controls the operation of mechanism which moves the control shaft 65 (Figure 23) one-twelfth of a rotation, the purpose of which 10 is to break the circuit through the solenoid 70 thereby unclutching the sleeve 106 from the motor connections. This partial rotation of the shaft 65 is brought about through the medium of a link 155 (Figures 2, 8, and 9) one end of which 15 is forked to engage the sleeve 106 while the other end is provided with an elongated recess 156 which embraces the shaft 65, the link thus being guided for reciprocatory movement. A spring 157 secured at one end to the link 155 and at 20 the other to an arm 158 projecting from the bracket 112 tends to move the link downwardly as viewed in Figures 8 and 9. The link is also provided with a roller 160 which rides on the circular surfaces of the disc 154 except when 25 one or the other of the notches therein are presented to the roller. When this occurs, the spring 157 causes the link 155 to move down and also causes a pawl 161 carried by an arm 162 of the link to engage a ratchet 163 secured to the shaft 30 65. The movement of the link and the size of the ratchet are so proportioned that when the link moves to the position shown in Figure 9, the ratchet is moved a sufficient distance to cause one of the points of a star wheel 164 to move 35 beyond the roller 165 carried by the arm 166 and urged into contact with the star wheel by a spring 167 as shown in Figure 23. The spring is sufficiently strong to cause the roller 165 to complete the movement of the shaft if the pawl 40 161 does not quite do so. The result of this movement of the shaft 65 is to cause the conducting segment 63 of disc 64 to be moved out of contact with the ends of the wires 62 and 66 and to cause a non-conducting segment of the 45 disc to be presented to the contacts thereby breaking the circuit through the solenoid 70. The spring 98 (Figure 12) immediately acts to move the hub 93 to a central position and the sleeve 106 stops. During this stoppage, the 50 record supported by the balls 132 is played on its underside by the upper stylus 144.

Retracting the upper tone arm and positioning the lower tone arm

It will be noted by reference to Figure 5 that the arm 150 of the bell crank controlling the operative position of a stylus is curved so that while the stylus is playing and thereby moving from position (b) or (c) (Figure 8) to the position (d) shown in said figure, the roller 151 is always in position to be under influence of the arm 150 to retract the stylus from the record when this becomes necessary.

The retraction of the stylus and the movement 55 of the tone arm back to normal position is brought about by mechanism whose movement is initiated by the stylus arm reaching the end 0 of the sound groove where it encounters an eccentric groove 170 (Figure 5). This eccentric groove causes the tone arm to vibrate and likewise the shaft 110 to which the tone arm is secured. An arm 171 (see Figure 7) is also secured to the upper end of the shaft 110 and carries a pawl 172 (Figure 8) adapted at the 5 time the tone arm is being vibrated by the eccentric

groove to engage a ratchet wheel 173 secured to the control shaft 65. A pawl 174 also engages the ratchet 173 to prevent retrograde movement thereof. As soon as the pawl 172 has been vibrated sufficiently to cause the ratchet 173 to move approximately three teeth a point of the star wheel 164 (Figure 23) has been moved far enough to be under influence of the roller 165 and the shaft 65 is then moved another one-twelfth of a rotation.

For convenience of description, the twelve segments of the disc 64 are numbered from 1 to 12, the conducting segment 12 being assumed to be in position to bridge the terminals of wires 62 and 63 when the operation is started. The first 10 movement of the shaft 65 brought about under control of the disc 154, resulted in non-conducting segment number 1 being positioned under the terminals of wires 62 and 63 with the consequent 15 breaking of the circuit through solenoid 70.

The vibration of the tone arm by the eccentric groove 170 causes the shaft 65 to rotate another 20 twelfth after the first record has been played.

This movement of the shaft 65 causes conducting segment number 2 of the disc 64 to be brought 25 into contact with the terminals of the wires 62 and 66 thereby again establishing a current through the solenoid 70, and the sleeve 106 is again rotated. The rotation of the sleeve 106 through the medium of the cam 146 causes the 30 retraction of the stylus from the record and through the medium of the cam 125 or 126, according to which cam has been the operative one, effects retraction of the tone arm to normal position indicated by position (a) (Figure 8). At 35 the same time the disc 154 moves the link 155 from the position shown in Figure 9 to the position shown in Figure 8 thereby retracting the pawl 161 ready to again advance the ratchet wheel 163 when the disc 154 has reached the 40 position shown in Figure 9. As soon as this happens the link again rotates the shaft 65 one-twelfth of a revolution which causes segment number 3 of disc 64 to break contact between the terminals of wires 62 and 63 and the circuit 45 through the solenoid 70 is again broken.

The shaft 65 in addition to the disc 64, also carries a disc 176 and a disc 177. It will also be noted that so far the shaft 65 has been moved through three increments of movement, each 50 movement being one-twelfth of a rotation, therefore the segment 3 of disc 176, which is a conducting segment, is in a position to bridge the terminals of the wires 178 and 179. Likewise, the segment 3 of the disc 177, which is likewise a 55 conducting segment, is in a position to bridge the terminals of the wires 180 and 181. The closing of the contact by the disc 176 causes a circuit to be established through a solenoid 182. The closing of the contacts of the disc 177 causes a 60 circuit to be closed through a solenoid 184 and through the solenoid 52 already described, the latter two solenoids being in series. By reference to Figure 7, it will be noted that the solenoid 52 raises the plunger 28 and causes the undermost 65 record supported by the balls 132 immediately to be released and dropped to the turn table 42. The solenoid 184 controls escapement mechanism which lowers the turn table 142 the distance of the thickness of a record each time that said 70 solenoid is energized. This particular escapement mechanism will be later described.

The closing of the circuit through the solenoid 182 operates the clutch hub 93 thereby establishing an operative connection with the sleeve 85. 75

This sleeve 85 is similar to the sleeve 106 and carries a series of cams which are duplicates of the cams carried by the sleeve 106 and whose construction and function has already been fully described. As soon as the sleeve 85 begins to rotate, its feeler cam 108 moves through about 45° as previously described before the feeler is permitted to move. During this time the escapement mechanism for the turn table 42 has had time to operate. The operations of playing a record on the turn table 42 follow the same general order as previously described. There are, however, some differences in the manner in which the shaft 65 controls the operation which need to be given further consideration. It will be recalled that at the time the circuit is closed through the solenoid 182, the segment 3 of the disc 176 bridges the contacts of the wires 178 and 179. The upper disc 64 does not further function to bridge the terminals of wires 62 and 63 until the shaft 65 has made three increments of movement. During these three increments the disc 176 exercises control.

After the lower feeler has operated to determine the extent of movement of the lower tone arm, and after this tone arm has been positioned and the stylus permitted to come into contact with the record, the sleeve 85 is stopped by the lower link 155 moving to the position shown in Figure 9. This causes the shaft 65 to be moved to position the number 4 segment of the disc 176 across the terminals of the wires 178 and 179 thereby breaking the circuit through the solenoid 182. After the record has been played in its lower position the vibration of the tone arm by the eccentric groove in the record causes the shaft 65 to be again rotated one-twelfth of a revolution and again establishes current through the solenoid 182 by reason of the segment 5 of the disc 176 bridging the terminals of the wires 178 and 179. The stylus is then lifted from the record, the tone arm is retracted to normal position and the disc 154 operates as previously described to move the shaft 65 another increment, opening the circuit through the solenoid 182 which results in stopping rotation of the sleeve 85. These successive movements of the shaft 65 have caused the segment 6 of the disc 64 to be again positioned to bridge the contacts between the wires 62 and 63. The under side of the lowermost record of the upper series of records is then played by the upper stylus and the various operations previously described are repeated. At this time the non-conducting segment 6 of the disc 176 is positioned to break the contact between the wires 178 and 179.

Turn table escapement mechanism

It has previously been pointed out that the turn table 42 is lowered as the records are deposited thereon and in order to accomplish this an escapement mechanism is provided constructed as follows: Extending upwardly from the casing (Figure 1) is a supporting bracket 186 carrying a plate 187 which forms a support for the lower end of the shaft 12. Attached to this plate and to the bracket 186 is a second plate 188 which supports a fork member 189 suitably apertured to provide clearance for the shaft 4 (see Figure 7). The right portion 190 (Figure 4) of the member 189 is slotted at 191 and acts as a guide for a sleeve 192 which loosely encircles the shaft 4. This sleeve is provided with an arm 193 engaging the slot 191 (see also Figure 4). The left portion 194 of the member 189 is rectangular in cross

section as indicated in Figure 4 and the lower portion of the sleeve is in the form of a collar which is forked at 195 and 196. Secured to the fork 195 is a member 197 having a handle 198 by which the sleeve 192 may be raised manually to 5 positions indicated by a scale 199 (Figure 13). The upper surface of the sleeve 192 provides a bearing for the turn table which turn table is raised or lowered as the sleeve is raised or lowered. The turn table and sleeve are connected 10 by a plate 200 having a projection 201 which engages loosely in a circular groove 202 in a bearing sleeve 203 of the turn table (see Figure 7). The sleeve 192 is provided with ratchet teeth 204 forming part of an escapement mechanism by 15 which the turn table is automatically lowered step by step under control of the solenoid 184. The solenoid 184 is supported by a bracket 184. The to the sleeve 192 by screws 205 (Figures 15 and 16). The bracket 206 carries a bearing 208 into 20 which is threaded a bearing pin 209. The armature 207 for the solenoid 184 pivots loosely on the pin 209. Carried by this armature 207 is a short shaft 210 about which pivots a pawl 211. The end of the armature 207 has its end remote from 25 the solenoid formed as a fixed pawl 212. Normally the pawl 211 supports the turn table by engaging the flat under side of a ratchet tooth 204 as indicated in Figures 15 and 16. When the solenoid 184 is energized the pawls 211 and 212 30 are rocked horizontally about the bearing pin 209 from the position shown in Figures 4 and 16 to the position in which the pawl 212 is positioned beneath a ratchet tooth, pawl 211 being withdrawn. At this point it may be stated that 35 the unit consisting of the armature 207, the pawls 211 and 212 are urged to the position shown in Figures 4 and 16 by the spring 214 connected at one end of the pawl 212 and at its other end to a strap 215 which secures the solenoid to the bracket 206. When the pawl 211 is withdrawn as above described, the sleeve 192 of the turn table drops a distance substantially one tooth of the rack 204. The parts are then in the position shown in Figure 17 and there is sufficient clearance to permit the pawl 211 to again return to its position shown in Figure 16 underneath the next higher ratchet tooth 204 when the solenoid 184 is de-45 energized and the spring 214 acts.

In order that the turn table 42 may be raised 50 to normal position after all of the records have been played, the pawl 211 is pivoted for rotation about the shaft 210. A spring 216 (Figure 15) normally tends to hold the pawl against a stop 55 217.

After the undermost record has been dropped on to the turn table 42 and the turn table lowered, the lower tone arm 122 is moved into playing position and the upper side of the record is 60 played by this tone arm while the record is supported on the turn table 42. After the record has been played, the sleeve 85 is given another 180° rotation and the cams carried by said sleeve operate to withdraw the stylus from the record, return the tone arm to normal position, as has 65 already been described.

The machine is designed at its full capacity to play ten records and the machine is so designed that when the last record has been played and the turn table given its last increment of 70 movement, means are brought into action which breaks the circuit through the solenoid 184 and thereby prevents any further automatic movement of the tone arms. The breaking of this circuit is under control of the arm 187 which as 75

shown in Figures 1 and 23 carries a pin 218 projecting from its side. This pin is so positioned that when the turn table has moved its last step the pin 218 contacts the member 219 of the switch 5 67 thereby breaking the circuit through the solenoid 70. As shown in Figures 1 and 14, the switch 67 is carried on a block 220 movable in a slot 221 of the casing. A knob 222 extending outside of the casing permits the block 220 to be positioned at different places along the slot as determined by the scale 199.

10 If it is desired to play five records for instance, instead of ten, the pointer 223 is positioned opposite the five on the scale 199 and therefore the 15 circuit through the solenoid 70 will be broken after the fifth record has been played.

What I claim is:

1. In a phonograph adapted to play both sides of a plurality of records successively, in combination, supporting means for one or more records, a second supporting means for one or more records, underneath and in vertical alignment with said first mentioned supporting means, stylus means for playing one side of a record 25 while in one of its supported positions and for playing the other side of the same record in its second supported position and means for transferring a record without reversal from the first to the second supporting means.

30 2. In a phonograph, supporting means for a stack of records, means for successively playing the underside of each record of said stack, a second supporting means, means brought into action upon the completion of the playing of a record 35 while in its first supported position to cause it to be transferred to the second supporting means, and means for playing the upper side of the records as they are successively transferred to said second supporting means.

40 3. In a phonograph, a supporting means for a stack of records, a second supporting means, means for automatically transferring a record from said first supporting means to the second supporting means a stylus for playing the under 45 side of a record while supported on said first mentioned supporting means, a second stylus for playing the opposite side of the same record

while carried on said second supporting means, and means for rotating the said supporting means in opposite directions simultaneously.

4. In a phonograph, means for supporting a plurality of records so as to leave the playing 5 surface of the undermost record unobstructed, a second support for a plurality of records situated beneath the first mentioned support, means for playing the underside of the lowermost record while supported on said first mentioned support, 10 means for dropping the played record to the second support and for playing the upper side of said record after being so dropped.

5. In a phonograph, in combination, two record supporting means for a plurality of records, a 15 stylus for playing one side of each record while supported on one said supporting means, a second stylus for playing the opposite side of each record while said record is carried on the second supported means, and means brought into action 20 upon completion of the playing of the record by the first mentioned stylus for causing the record played thereby to be transferred without reversal from said first supporting means to the other.

6. In a phonograph, in combination, a plural- 25 ity of superposed supports for a plurality of records, a plurality of styls, means for bringing one stylus into position to play one side of a record while on the upper support, means for moving the stylus beyond the records on the upper sup- 30 port and for dropping a played record without reversal on to the lower support, and means for bringing the other stylus into position to play the opposite side of the same record while on the lower support. 35

7. In a phonograph, a supporting means for a stack of records, a second supporting means, means for automatically transferring a record without reversal from the first supporting means to the second supporting means, stylus means 40 for playing the under side of a record while supported on said first mentioned supporting means and for playing the opposite side of the same record while supported on said second mentioned supporting means, and means for rotating the 45 said supporting means in opposite directions.

ARTHUR C. ANSLEY.
